United States Patent Office.

WILLIAM HORROCKS, OF POUGHKEEPSIE, NEW YORK.

Letters Patent No. 80,180, dated July 21, 1868.

IMPROVEMENT IN THE MODE OF ATTACHING CARRIAGE-TOPS.

The Schedule referred to in these Letters Patent and making part of the same.

TO ALL WHOM IT MAY CONCERN:

Be it known that I, WILLIAM HORROCKS, of Poughkeepsie, in the county of Dutchess, and State of New York, have invented a new and useful Improvement in Attaching Carriage-Tops to the Rails or Bodies; and I do hereby declare that the following is a full, clear, and exact description thereof, which will enable those skilled in the art to make and use the same, reference being had to the accompanying drawings, forming part of this specification, in which—

Figure 1 represents a side elevation of my improved carriage-top attachment.

Figure 2 is a transverse vertical section of the same.

Similar letters of reference indicate corresponding parts.

This invention relates to a new manner of securing the carriage-slat irons to the rails or bodies of carriages, and consists in pivoting each slat separately to a disk or knob by a separate pin or pivot. Thereby the inconvenience and mechanical difficulty are avoided, which were always experienced when the slat-irons were fastened by means of one common pivot, which pivot had to be made extraordinarily strong and clumsy, while now each pin can be made light.

A, in the drawing, represents the pin projecting from the railing or carriage-body to receive the lower ends of the slats.

B C D E are the four slats formed at the lower ends, respectively, of the four bows, F, G, H, and I, of the carriage-top. The number of slats and bows may, however, be varied.

The lower end of each slat is pivoted by a separate pin, a, to a disk or shoulder, b, formed or secured on the pin A in any suitable manner.

The lower ends of the bows are or may be curved. Those in front of the pin A are bent backward and those in its rear bent forward, as indicated in fig. 1, in which B and C are the slats in front, and D E those in rear. This is for the purpose of allowing all slats to stand in the required position, although their lower ends may be brought near together, and for allowing the front slats to be readily folded back, as indicated in red lines in fig. 1.

The pins a are fastened to either the disk b or c. The latter covers and protects the lower parts of the slats on their outer sides, as shown in fig. 2.

By not having the slats all connected by the same pivot, the annoying rattling of the carriage-top will be avoided. The outer or covering-disks c are fastened to the pin A by means of a nut, d.

I claim as new, and desire to secure by Letters Patent—

Securing the slat-irons of a carriage-top to the supporting-pin A, by means of the separate pivots a, formed upon either of the disks b c, which fit over the pin A, both disks being clamped together upon the slat-irons by means of the nut d, as herein described, for the purpose specified.

WILLIAM HORROCKS.
